UNITED STATES PATENT OFFICE.

MILTON H. SHOENBERG, OF SAN FRANCISCO, AND FRANK TALCOTT, OF BURLINGAME, CALIFORNIA, ASSIGNEES TO MAJESTIC ELECTRIC DEVELOPMENT COMPANY, A CORPORATION OF CALIFORNIA.

CURRENT DETERMINATOR AND INDICATOR.

1,291,197.

Specification of Letters Patent. Patented Jan. 14, 1919.

Application filed August 13, 1917. Serial No. 186,070.

To all whom it may concern:

Be it known that we, MILTON H. SHOENBERG and FRANK TALCOTT, citizens of the United States, residing at San Francisco and Burlingame, in the county of San Francisco and San Mateo and State of California, respectively, have invented certain new and useful Improvements in Current Determinators and Indicators, of which the following is a specification.

Our invention relates to devices for determining the character of electrical currents, whether alternating or direct, and indicating whether it is of a certain predetermined maximum voltage or less.

In the accompanying drawing, Figures 1 and 5 are diagrammatic illustrations of apparatus embodying our invention, in which the indications are recorded upon a suitable record sheet, while Fig. 3 shows a visual indicator; Figs. 2 and 4 are diagrammatic illustrations of record cards or sheets that may be employed; and Fig. 6 is an end elevation of the case or housing for our indicator illustrated in Fig. 5 and having the record sheets in the form of a continuous roll attached to the case.

Referring first to the visual indicator illustrated in Figs. 3 and 4, the apparatus comprises a transformer provided with terminals 3, 4 which may be connected to the line conductors 1, 2 to be tested, a lamp 5 being in series with the primary coil 7 and a lamp 6 in the circuit of the secondary coil 8. The transformer and lamps may be inclosed in a suitable case or housing having a side or face 10 over which a card or sheet 12 may be placed, so that the lamp 5 will appear through the aperture 5^a and the lamp 6 through the aperture 6^a. The card may be provided with suitable data, such as indicated, which may be filled in by the mechanic or party making the test.

It will be evident to those familiar with electrical phenomena, that the lamp 6 in circuit with the secondary of the transformer will glow when the terminals 3, 4 are connected to an alternating circuit, while the lamp 5 will remain unlighted because the impedance of the primary 7 will not permit a sufficient amount of current to pass to heat the filament to incandescence although permitting a magnetizing current to energize

the primary. On the other hand, if the terminals are connected to a direct current source, the lamp 5 will glow, while the lamp 6 will remain unlighted, since no current will be induced in the secondary coil 8.

In Fig. 5, we have substituted resistances 5', 6' for the lamps in the arrangement of Fig. 3. The record cards or sheets 12^a may be in the form of a roll 14, secured either inside or outside of the case or housing 15 which may also contain the transformer coils and resistances. If the terminals are connected to a direct current source, the resistance wire 5' will be heated, while no current will be induced in the secondary coil of the transformer; while if the terminals are connected to a source of alternating current, the impedance of the primary coil will permit only a small current to flow, not sufficient to heat the wire 5', the current induced in the secondary coil 8, however, being sufficient to heat the resistance wire 6'. The paper sheet 12^a is placed directly over the resistance wires and will be burnt or scorched by one or the other resistance wire, thereby recording an indication of the character of the current flowing in the mains 1, 2. The data designating the place and time may be written in the appropriate blanks on the record sheet, which may then be torn off and a new sheet unrolled.

Instead of resistance wires, we may employ heating or burning elements which fuse, blow or burn out upon the passage of the predetermined current. In Fig. 1, the indicating elements 5'' and 6'' may be formed of a fusible metal which will blow or fuse upon the flow of a certain current, or of some electrical conductor which will burn out, such as a graphite ink. In either case the fusing or burning out of the element 5'' or 6'' will produce a scorch or burn upon the paper sheet 12^b, placed thereover, the indication appearing upon the top side of the sheet in the corresponding circle adjacent the appropriate designation A. C. or D. C. The fuse or other destructible conductor may then be replaced and a new record placed in position thereover in readiness for the next test.

It is also frequently desirable to know whether the line voltage is 110 volts or 220 volts. This may be indicated by providing

22
 an element 16 which is connected directly across the terminals and having in circuit therewith a fixed non-inductive resistance 17, which is adjusted to permit the element 5 17 to fuse or burn only when the voltage reaches substantially 220 volts. Upon the flow of current corresponding to 220 volts, the paper 12^b will be scorched within the circle thus designated. Instead of scorching the paper, other markings or indications may be caused upon chemically prepared paper.

10 The advantages and usefulness of this invention will be appreciated by electricians, 15 linemen and engineers who are required to connect apparatus to electrical circuits in which current is flowing. It is frequently desirable to determine the character of the current and also which of the two usual voltages is connected to the line conductors. 20 Likewise it is often desirable that the mechanic shall file a record with his report of the work done. This apparatus may be made in very compact form, if necessary 25 small enough to be placed in one's pocket. We have described several forms for the purpose of clearly disclosing our invention and the manner of applying or using it, but desire it to be understood that other modifications and changes may be made within 30 the scope of our claims and without departing from our invention.

We claim:—

1. Apparatus for determining the character of an electric current having terminals 35 adapted to be connected to electric conductors, comprising devices responsive to the flow of current, one of said devices being in direct connection with the terminals and 40 the other device being inductively connected thereto.

2. Apparatus for determining the character of an electric current having terminals 45 adapted to be connected to electric conductors, comprising thermally responsive devices, one of said devices being connected conductively with the terminals to respond to a direct current, and another device connected to the terminals to respond inductively to an alternating current.

3. Apparatus for determining the character of an electric current having terminals 50 adapted to be connected to electric conductors, comprising thermally responsive de-

vices, one of said devices being connected 55 conductively with the terminals with an interposed impedance to respond to a direct current, and another device connected to the terminals inductively to respond to an alternating current. 60

4. Apparatus for determining the character of an electric current having terminals adapted to be connected to electric conductors, comprising thermally responsive devices, one of said devices being connected 65 conductively with the terminals to respond to a direct current, and another device connected to the terminals to respond inductively to an alternating current, and a medium superposed upon said devices which 70 is affected by the responsive device.

5. Apparatus for determining the character of an electric current having terminals adapted to be connected to electric conductors, comprising thermally responsive devices, one of said devices being connected 75 conductively with the terminals with an interposed impedance to respond to a direct current, and another device connected to the terminals to respond inductively to an alternating current, and a fibrous sheet adjacent said devices which is chemically changed by 80 the heat of the responsive device.

6. Apparatus for determining the character of an electric current having terminals 85 for connection to electric conductors, comprising thermally responsive devices, a transformer having its primary coil connected to the terminals, one of said devices being in circuit with said primary coil, and another 90 95 of said devices being in circuit with the secondary coil of said transformer.

7. Apparatus for determining the character of an electric current having terminals for connection to electric conductors, comprising thermally responsive devices, a transformer having its primary coil connected to the terminals, one of said devices being in series with said primary coil, another of said devices being connected in 100 shunt thereto, and a third device being connected to the terminals of the secondary coil of said transformer.

In testimony whereof we affix our signatures.

MILTON H. SHOENBERG.
